Primary Examiner—Robert M. Spear(74) *Attorney, Agent, or Firm*—Volpe and Koenig, P.C.(57) **CLAIM**

The ornamental design for a frame for display element, as shown and described.

DESCRIPTION

FIG. 1 is a perspective view, from front and above, of a frame for a display element showing our new design.

FIG. 2 is a reduced scale front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines shown in FIGS. 1-7 represent environmental subject matter and form no part of the claimed design. The dotted lines shown in FIGS. 1-6 represent borders between claimed and unclaimed subject matter and form no part of the claimed design.
